UNITED STATES PATENT OFFICE.

EUGÈNE STUBBS, OF CALAIS, FRANCE.

DESIGN FOR LACE FABRIC.

SPECIFICATION forming part of Design No. 23,945, dated January 8, 1895.

Application filed December 12, 1894. Serial No. 531,599. Term of patent 3½ years.

To all whom it may concern:

Be it known that I, EUGÈNE STUBBS, a citizen of France, and a resident of Calais, France, have invented and produced a new and original Design for Lace Fabric, of which the following is a specification, reference being had to the accompanying drawing, showing a part thereof.

The drawing represents a piece of my newly designed lace fabric.

The leading feature of my design consists of a lace fabric having a net top, rows of scalloped ornaments, and a row of leafed ornaments, the ornaments forming arabesques with open effects.

a, is a net top, and *b*, *c*, and *d*, three parallel rows of ornaments, arranged to break line. The ornaments *b*, have a scalloped edge and are in configuration similar to the ornaments

c. The ornaments *d*, are larger and are composed of a voluted core and outer radiating leaves. The ornaments *b*, *c*, *d*, are connected to form arabesques and cut out effects as shown. Between the ornaments *d*, are placed rings *e*, arranged in groups of three.

What I claim is—

The design for a lace fabric substantially as herein shown and described.

In testimony that I claim the foregoing as my invention I have signed my name, in presence of two witnesses, this 15th day of November, 1894.

EUGÈNE STUBBS.
